UNITED STATES PATENT OFFICE.

KATHERINE R. O'KANE, OF PHILADELPHIA, PENNSYLVANIA.

DUPPLICATING-MACHINE.

1,285,340.

Specification of Letters Patent. Patented Nov. 19, 1918.

Application filed June 12, 1913. Serial No. 773,192.

To all whom it may concern:

Be it known that I, KATHERINE R. O'KANE, a citizen of the United States, residing at Philadelphia, in the State of Pennsylvania, have invented a certain new and useful Improvement in Duplicating-Machines, whereof the following is a specification, reference being had to the accompanying drawings.

My improvement is particularly applicable to printing machines of the type known commercially as the "Multigraph" comprising a rotary printing cylinder having a series of undercut channels in its perimeter extending parallel with its axis to receive complementary shaped flanged type which said cylinder presents in opposition to the other member of the printing couple. As ordinarily constructed, the only means with which such a machine is provided for printing lines at right angles to the lines of letter type consists of type fitted to the channels and having dash faces. Consequently, a series of such separate type must be used to print a line of greater extent than the dash carried by the face of a single type, and, unless said line type are accurately set and provided with means to hold them in alinement they print a broken line instead of the continuous line desired.

Therefore, it is the object of my invention to provide such a machine with means to present a continuous printing face to print lines at right angles to the lines of words, and, as hereinafter described, such means includes a rule strip curved to fit circumferentially upon said printing cylinder and preferably having means fitting in said undercut channels thereof adapted to retain it in set position.

My invention comprises the various novel features of construction and arrangement hereinafter more definitely specified.

In the drawings; Figure I is a side elevation of a rotary printing cylinder and a reciprocating plane platen, such as are employed in a machine of the type specified.

Fig. II is a fragmentary plan view of a portion of said cylinder with letter type and rule strips set therein.

Fig. III is an end view of the elements shown in Fig. II.

Fig. IV is a detached view of a complete rule strip such as shown at the left hand

side of Figs. II and III, but on a smaller scale.

Fig. V is a detached view of a complete rule strip such as shown at the right hand side of Figs. II and III, but on a smaller scale.

Fig. VI is a sectional view of said strip taken on the line VI, VI, in Fig. V.

Fig. VII is a vertical transverse sectional view of a rotary printing cylinder showing a modified form of my invention.

Figs. VIII and IX are fragmentary vertical transverse sectional views of a printing cylinder showing different modified forms of my invention.

Fig. X is a fragmentary longitudinal sectional view taken on the line X, X, in Fig. VII, but on a larger scale.

Fig. XI is a fragmentary longitudinal sectional view taken on the line XI, XI, in Fig. IX.

Fig. XII is a fragmentary elevation of one end of a rule strip, resembling that shown in Fig. VII, but having its printing surface in unitary relation with its supporting band, like the strip shown in Figs. II, III and IV.

The rotary printing cylinder 1, has the undercut channels 2, extending in its perimeter parallel with its axis, and, each type 3, 4, and 5, is provided with flanges 6 complementary to and fitted in said channels. The rule strip 8 being curved to fit the circumference of said cylinder 1 is held thereon between said type merely by frictional engagement of its flanges 9 therewith; said type being clamped together in the direction of the length of the lines of words by any suitable means. However, the rule strip 11 which is likewise curved to fit the circumference of said cylinder 1 and provided with flanges 12 for engagement between said type, is also provided with lugs 14 which fit in said undercut channels 2 so as to be retained by the overlapping ledges 15 engaging the flanges 16 on said lugs; so that said strip 11 may be retained on the cylinder independently of said type.

It may be observed that the flanges 9 and 12 of said strips 8 and 11, which extend in contact with the circumference of said cylinder 1 support the printing edges 18 and 19 of said strips 8 and 11 in a plane at right angles to the perimeter of said cylinder 1.

so as to insure the rectitude of the lines printed by said strips.

I find it convenient to make the rule strips above described, by rolling them from 5 brass or other suitable metal with the respective flanges 9 and 12 thereof straight and then curving said strips to fit said cylinder, by another rolling operation. However, it is to be understood that said strips 10 may be otherwise manufactured, for instance, they may be cast of ordinary type metal or other suitable material.

When the type have been assembled in 15 said cylinder 1 in the desired relation the inked ribbon 20 is drawn over the type faces and secured by connection with the rollers 21 and 22 which are mounted in said cylinder as indicated in Figs. I and VII, so that when a sheet of paper is interposed 20 between the platen and said cylinder and the latter turned until the platen is shifted to the position shown in dotted lines in Fig. I, said sheet is imprinted with an impression made from said type and rule strips 25 through said inked ribbon.

The rule strips above described have printing surfaces which are in rigid relation with their supporting flanges extending laterally upon opposite sides thereof and 30 bearing upon the printing drum, and the means connecting said strips with said drum independently of said type are rigid portions of said strips. However, it is to be understood that the printing surfaces of 35 the strips may be resilient and that separable and resilient means may be employed for connecting the strips with said drum. For instance, as shown in Fig. VII the printing surface of the rule strip 25 is a 40 cord connected with and carried by the band 26, conveniently formed of sheet metal, which forms supporting flanges extending laterally upon opposite sides of said printing surface 25 as shown in Fig. X. I prefer to connect said printing surface 25 with 45 said band 26, intermediate of its length, by means 27 adhering to both of said elements. However, it is to be understood that said printing surface 25 may be formed by a 50 cord or wire which may be attached to said band only at its ends, or intermediate of its length as indicated in Fig. X. Said rule strip shown in Fig. VII has no means connecting it with said drum by engagement in 55 said channels 2, but is connected with said drum by the resilient hooks 29, conveniently formed of wire, pivotally connected with said band 26 by extension through the bights 30 at the ends thereof. Said hooks 60 extend beneath said outer curved surface of the drum which is formed to carry the type, in engagement with the sectoral ledges 31 of the drum, and it is to be understood that said hooks are flexible and resilient 65 not only in the direction necessary for them

to flex to receive said ledges 31, but also in the direction of the length of said band 26, so as to resiliently maintain the latter taut over said curved surface of the drum formed to carry the rows of type.

As shown in Fig. X said rule strip including the elements 25 and 26 is held between the individual type 3 set in said channels 2. However, as above described, 70 said rule strip has means connecting it with 75 said drum 1 independently of said type.

Although I have shown said rule strip in Fig. X as formed of two primarily separate elements respectively constituting the printing surface 25 and the supporting flanges 80 26; it is to be understood that said elements may be in unitary relation as indicated in Fig. XII, wherein they are pressed from a single strip of sheet metal. Moreover, although I have shown the several rule strips 85 aforesaid with their printing surfaces 25 coextensive with their supporting flanges; it is to be understood that they may be made of less extent. However, it is obvious that unless the printing surface thereof is 90 coextensive with a plurality of the type channels 2 and the rows of type set therein, it would be more convenient to employ a single column dash type of the prior art; the advantage of my invention being that 95 the column rule may be formed in accordance therewith which is less costly than a column rule formed of such dash type and which may be set in a fraction of the time required to set a column rule formed of such 100 type.

Of course, if said printing surface 25 of the rule strip last described be formed of cord, it would be resilient, but if formed of wire it would not be resilient, assuming that 105 its supporting band 26 be in intimate contact with the curved surface 32 of the drum. However, as indicated in Fig. VIII the printing surface 34, which may be formed of wire, is resiliently supported by the band 110 35, conveniently formed of rubber. The rule strip having said printing surface 34 curved in concentric relation with the drum 1 may be held between said flanged type 3, 4, and 5 as above described, but is also provided with end lugs 36 fitted in said channels 2 and having flanges 37 engaged by the overlapping ledges 15 in said channels. Said rule strip is also provided with separable and resilient means for connecting it 115 with said drum, including the wedge blocks 39 which are conveniently formed of molded rubber. Said resilient band 35 is also conveniently provided with end lugs 41 extending into said channels 2 and conveniently secured by the wedge blocks 42 which may be separable and resilient like said blocks 39.

As shown in Figs. IX and XI a rule strip having a printed surface 45 may be formed 120

of a cord or wire without supporting flanges bearing upon the surface of the drum although curved in concentric relation with the latter; said strip being supported by 5 the blank space type 5 and projecting above the latter to the same extent as the printing faces of said type 3 and 4. Said rule strip having the printing surface 45 is provided with lugs 46 extending in the channels 2 and 10 having the flanges 47 engaged beneath the overhanging ledges 15 in said channels. Said strip is also conveniently provided with separable and resilient means for connecting it with said drum independently of 15 said type, including the wedge blocks 49.

I do not desire to limit myself to the precise details of construction and arrangement herein set forth as it is obvious that various modifications may be made therein without 20 departing from the essential features of my invention as defined in the appended claims.

I claim:—

1. In a duplicating machine, the combination with a member having a curved surface 25 formed to carry rows of type parallel with its axis; of a device extending transversely with respect to said axis, coextensive with a plurality of said rows of type, having a printing surface curved in concentric relation 30 with said axis, said device having end portions arranged to extend beneath said surface, and means connecting said device with said member independently of said type.

2. In a duplicating machine, the combination with a member having a curved surface formed to carry rows of type parallel with its axis; of a rule strip extending transversely with respect to said axis, coextensive 40 with a plurality of said rows of type, having a printing surface curved in concentric relation with said axis, said rule strip having end portions arranged to extend beneath said surface, and means connecting said rule strip with said member independently of said type.

3. In a duplicating machine, the combination with a member having undercut channels in a curved surface formed to carry 50 rows of type parallel with its axis; of a device extending transversely with respect to said axis, coextensive with a plurality of said rows of type, having a printing surface curved in concentric relation with said axis, said device having end portions arranged to extend into said channels beneath said surface, and means connecting said device with said member independently of said type.

4. In a duplicating machine, the combination with a member having a curved surface formed to carry rows of type parallel with its axis; of a device extending transversely with respect to said axis, coextensive with a 55 plurality of said rows of type, having a

printing surface curved in concentric relation with said axis, said device having end portions arranged to extend beneath said surface, and separable resilient means connecting said device with said member independently of said type. 70

5. In a duplicating machine, the combination with a member having a curved surface formed to carry rows of type parallel with its axis; of a device extending transversely 75 with respect to said axis, coextensive with a plurality of said rows of type, having a printing surface curved in concentric relation with said axis, said device having end portions arranged to extend beneath said 80 surface, and separable means connecting said device with said member independently of said type.

6. In a duplicating machine, the combination with a member having a curved surface 85 formed to carry rows of type parallel with its axis; of a device extending transversely with respect to said axis, coextensive with a plurality of said rows of type, having a printing surface curved in concentric relation 90 with said axis, said device having end portions arranged to extend beneath said surface, and resilient means connecting said device with said member independently of said type. 95

7. In a duplicating machine, the combination with a rotary printing drum having a plurality of undercut channels in its periphery, of type having flanges fitted in said channels; and, a rule strip having a printing surface curved in concentric relation with said drum, held between said flanged type, and supporting flanges extending laterally upon opposite sides of said printing surface and bearing upon said drum, and, 100 lugs on said rule strip fitted in said channels.

8. In a duplicating machine, the combination with a rotary printing drum having a plurality of undercut channels in its periphery, of type having flanges fitted in said 105 channels; and, a rule strip having a printing surface curved in concentric relation with said drum, held between said flanged type, and supporting flanges extending laterally upon opposite sides of said printing surface and bearing upon said drum. 110

9. In a duplicating machine, the combination with a rotary printing drum having a plurality of undercut channels in its periphery, of type having flanges fitted in said 120 channels; and, a rule strip having a printing surface curved in concentric relation with said drum, held between said flanged type, and a supporting flange extending laterally and bearing upon said drum. 125

10. In a duplicating machine, the combination with a rotary printing drum having a plurality of undercut channels in its periphery, of type having flanges fitted in said 130 channels; and, a rule strip having a print-

ing surface curved in concentric relation with said drum, held between said flanged type, and having lugs fitted in said channels.

11. In a duplicating machine, the combination with a rotary printing drum having a plurality of undercut channels in its periphery, of type having flanges fitted in said channels; and, a rule strip having a printing surface curved in concentric relation 10 with said drum, having means connecting it with said drum independently of said type.

12. In a duplicating machine, the combination with a rotary printing drum having a plurality of undercut channels in its periphery, of type having flanges fitted in said 15 channels; and, a rule strip having a printing surface curved in concentric relation with said drum, having separable resilient means connecting it with said drum independently of said type.

13. In a duplicating machine, the combination with a rotary printing drum having a plurality of undercut channels in its periphery, of type having flanges fitted in said 25 channels; and, a rule strip having a printing surface curved in concentric relation with said drum, having separable means connecting it with said drum independently of said type.

14. In a duplicating machine, the combination with a rotary printing drum having a plurality of undercut channels in its periphery, of type having flanges fitted in said channels; and, a rule strip having a printing 35 surface curved in concentric relation with said drum, having resilient means connecting it with said drum independently of said type.

15. In a duplicating machine, the combination with a member having a curved surface formed to carry rows of type parallel 40 with its axis; of a device extending transversely with respect to said axis, coextensive

with a plurality of said rows of type, having a resilient printing surface curved in 45 concentric relation with said axis, said device having end portions arranged to extend beneath said surface, provided with means connecting said device with said member independently of said type.

16. In a duplicating machine, the combination with a rotary printing drum having a plurality of undercut channels in its periphery, of type having flanges fitted in said 55 channels; and, a member having a printing surface curved in concentric relation with said drum, having means connecting it with said drum independently of said type.

17. A column rule for use on a drum-like holder having longitudinal undercut channels, comprising an arcual strip, and holding means adapted to occupy some of such channels and extend into the undercut portion thereof.

18. A printer's rule for use on a rotary printing machine comprising an arcual strip concentric of the printing cylinder, and inwardly projecting members rigid with the strip having laterally projecting feet adapted to engage beneath the heads of rails on 70 the printing cylinder.

19. The combination, with a rotary printing drum having rails parallel with its axis, of a printer's rule having a strip curved concentrically of the drum, and members 75 extending inwardly from the strip into the space between rails and projecting circumferentially in such space to engage beneath the rail heads.

In testimony whereof, I have hereunto signed my name at Philadelphia, Pennsylvania this eleventh day of June, 1913.

KATHERINE R. O'KANE.
